UNITED STATES PATENT OFFICE.

JOSEPH C. DANE AND WILLIAM L. CARD, OF LA CROSSE, WISCONSIN.

AMALGAMATOR.

SPECIFICATION forming part of Letters Patent No. 284,392, dated September 4, 1882.

Application filed July 31, 1882. (No model.)

To all whom it may concern:

Be it known that we, JOSEPH C. DANE and WILLIAM L. CARD, both of La Crosse, in the county of La Crosse and State of Wisconsin, 5 have invented a certain new and useful Improvement in Amalgamators, of which the following is a full, clear, and exact description, reference being had to the accompanying drawings, forming part of this specification, and in 10 which—

Figure 1 is a side elevation. Fig. 2 is a longitudinal section taken on line 2 2, Fig. 3. Fig. 3 is a front end view. Fig. 4 is a vertical section taken on line 4 4, Fig. 2. Fig. 5 is an enlarged detail view illustrating the bearing and supporting rollers. Figs. 6 and 7 are enlarged detail views of the gatherer and polisher, Fig. 6 showing a top view, and Fig. 7 being a section on line 7 7, Fig. 6. Figs. 8 15 and 9 illustrate a simplified form of our invention. Fig. 10 is a diagram illustrating the manner in which the sand, &c., travels through the tapering cylinders, as hereinafter more fully described.

25 Our invention relates to an apparatus for dry amalgamation, or amalgamating without the use of water; and our invention consists, broadly, in one or more tapering cylinders which are secured to a revolving frame, and 30 whose inner surfaces are amalgamated, the lower part of the inside of the discharge end of each cylinder being higher than the lower part of the inside of the receiving end, while the axis, or a line drawn through the center of 35 the cone or cones, is lower at the discharge than at the receiving end or ends. A brush and gatherer is arranged within the cone or cones, as more fully described hereinafter.

In the drawings, 1 is a suitable feeding device.

40 A represents one or more cylinders, (we have shown five,) each formed in the shape of a frustum of a cone, the small end of one entering the large end of the next. They are removably connected together by longitudinal strips B, held in place by rings C, made from angle-iron, to which they are secured by bolts, or by other suitable means. The cylinders are held 45 from endwise movement by rings D, secured to 50 the ends of the strips B, as shown. The strips B are supported by grooved wheels E, journaled to rectangular frames F, one near each

end. The grooved wheels receive the vertical flange of the angle-iron rings, and thus the cylinders can be revolved, and as a means of 55 revolving them we have shown a grooved pulley, G, between which and any suitable motive power connection may be made, secured to the strips B. The cylinders are preferably made of copper, or of other material lined with 60 copper, so that the quicksilver will adhere perfectly to their inner surfaces. When in working position, the receiving end of the apparatus is raised by suitable means, as shown in Fig. 1, which gives an incline toward the 65 delivery end to the axis or centers of the cylinders, while the lowest part of the receiving end of each is lower than the lowest part of its discharge end, as before stated, the function being fully set forth in the below description 70 of the operation of the machine.

Secured to the frames F is a strip or rail, H, which supports, by means of connecting arms or braces I, a combined gatherer and brush or polisher, which traverses the insides of the cylinders. It is constructed as follows: K is a 75 back strip, to which the ends of the supporting-arms I are secured, and L are lower strips or blocks, one for each cylinder, to whose surface they quite or nearly conform. They are 80 connected together by bolts M, or by other suitable means, and on them are secured copper plates N, one for each cylinder, formed, as shown in Figs. 6 and 7, to fit the interior of the cylinders or shells, and between the 85 strips and beneath the plates N are clamped layers O, of cotton ducking or other suitable material.

The operation of the apparatus is as follows: Having a proper screen and hopper or feeding device at the receiving end of the machine, the sand and gravel containing gold will enter the largest end of the first cone or cylinder, and as the machine revolves will be carried upward on the ascending side as far as or 90 somewhat above a concentric line at right angles to the axis of the cylinders, and then, rolling over, will descend perpendicularly, (see Fig. 10,) thus moving a little nearer the exit end of the apparatus at each ascent and 95 descent, until finally discharged. In the meantime, however, every particle of the material will, by the peculiar rolling motion imparted, be brought many times in contact with the in- 100

terior surfaces of the cylinders, which, being amalgamated, will gather and separate the gold from the gravel, &c., and then as these surfaces pass down upon the opposite side the 5 particles of gold which have adhered thereto will be taken off at each revolution by the gatherer and accumulate upon the upper sides of its amalgamated copper plates N. Mercury for amalgamating the cylinders and gatherer may be introduced in any suitable way.

It is important that an amalgamated surface for gathering gold particles should be kept clean and bright, and in our apparatus this is done by the ducking or other suitable material, O.

Figs. 8 and 9 illustrate a simplified form of our invention, wherein no gatherer and polisher are employed. A single tapering cylinder, A, made of wood, is supported on rollers A', which are secured to a suitable frame, one of which has a crank, A², by which the cylinder is revolved. The ends of the cylinder have openings A³ A⁴, respectively, and its axis is lower at the delivery than at the receiving end, 25 while its interior lower portion is the lowest at its receiving end, as in the main invention. A⁵ are triangular blocks secured to the large end of the cylinder, as shown. The sand containing the gold and mercury is put into the 30 cylinder, and as it is revolved they are carried up its ascending side and fall perpendicularly, as already described, the sand gradually getting nearer the discharge end of the cylinder, while the mercury, carrying the gold with 35 it, will flow back down to the receiving end.

It is important that the discharge ends of the cylinders have inturned flanges a, which prevent the mercury escaping, but do not interfere with the sand, &c., being discharged. 40 (See Fig. 10.)

We claim as our invention—

1. A tapering amalgamating-cylinder open at each end, and mounted with its axis inclined downwardly toward the discharge end and its bottom inclined downwardly toward 45 its receiving end, as set forth.

2. In combination with a suitable feeding device, a tapering amalgamating-cylinder in which the axis and the bottom incline in opposite directions, for the purpose of moving 50 the matter gradually along the inner face of the cylinder, as set forth.

3. A tapering amalgamating-cylinder mounted to discharge at its smaller end, in combi-

nation with a suitable supporting-frame to 55 incline it toward the discharge end, the bottom of the cylinder being inclined upwardly toward the discharge end to provide a trough, substantially as shown and described.

4. In an amalgamator, in combination with 60 a suitable cage or frame and a feeding device, one or more tapering cylinders secured to and carried within said frame, having end receiving and discharging openings, formed to receive at the large end and discharge at the 65 small end, the axis of the smaller or discharging end being lower than that of the larger or receiving end, while the lowest interior surface is at the larger or receiving end, as and for the purpose described and set forth.

5. In an amalgamator, a feeding device and 70 two or more tapering cylinders, constructed with end receiving and discharging openings, in combination with an outer rotatable frame, the smaller or discharge end of one cylinder 75 entering a short distance into the larger or receiving end of the next, and the axis of the whole inclining downward toward the discharging end of the apparatus, while the lowest interior of each cylinder is at the receiving end, as and for the purpose set forth.

6. In an amalgamator, one or more tapering cylinders with receiving and discharging 80 openings, its securing-frame, and means for 85 rotating the same, in combination with a stationary gatherer and polisher which traverses the inside of the cylinder or cylinders, as and for the purpose set forth.

7. In an amalgamator, two or more tapering cylinders, A, with open ends, frame F, 90 longitudinal supporting-strips B, rings C, wheels E, secured to the frame F, and receiving the rings C, rail H, secured to the frame by connecting-arms I, and combined gatherer and polisher K L N O, all made and arranged 95 substantially as shown and described.

8. In an amalgamator having tapering cylinders, the combined gatherer and polisher, consisting of strip K, block L, copper plates N, and ducking O, arranged and clamped together, substantially as shown and described, and secured in place within the cylinders, as set forth.
